ABSTRACT OF THE DISCLOSURE

A hydropneumatic flushing cistern comprising a container, portions of which define a water inflow port to feed water into said container, a valve seat at the base of the container which bounds a water outflow port of through-flow area which is greater than that of the inflow port for leading flushing water from the container, a valve closure member in the container movable between a closed position in which it contacts the seat and closes the outflow port and an open position which is above the closed position, biasing means urging the closure member away from the open position towards the closed position, a cover for the valve closure member, portions of which together with the valve closure member define a chamber, a duct communicating with the chamber to lead water thereto and a flow-producing means to produce a flow of water from the chamber so as to cause the upward force on the closure member to exceed the downward force on same and open the closure.

According to the present invention, there is provided a hydro-pneumatic flushing cistern, comprising a container, portions of said container defining a water inflow port for feeding water to the interior of said container, a valve seat at the base of said container bounding a water outflow port of greater through-flow area than is said inflow port for leading flushing water from said container, a valve closure member in said interior movable between a closed position in which it contacts said seat and closes said outflow port and an open position which is above said closed position, biasing means urging said closure member away from said open position and towards said closed position, a cover covering said valve closure member, portions of said cover and said valve closure member defining therebetween a chamber, duct means communicating with said chamber for leading water thereto, and flow-producing means for producing a flow of water from said chamber such as to cause the upward force on said closure member to exceed the downward force on said closure member, whereby said closure member is opened.

In order that the invention may be clearly understood and readily carried into effect, reference will now be made, by way of example, to the accompanying drawings, in which:

FIGURE 1 is a fragmentary vertical axial section through a hydro-pneumatic flushing cistern of a water-closet, with a pilot valve and a water outflow valve in closed conditions;

FIGURE 2 is a detail of FIGURE 1, but illustrates a first stage in the initiation of the flushing operation;

FIGURE 3 is a fragmentary section taken on the line 3—3 of FIGURE 2;

FIGURES 4 and 5 are similar views to FIGURE 2, but illustrate respective second and third stages in the initiation of the flushing operation;

FIGURE 6 is a view similar to FIGURE 1, but showing a first modified version of the cistern;

FIGURES 7 and 8 are a detail of FIGURE 6, but illustrate respective stages in the initiation of the flushing operation;

2

FIGURE 9 is a view similar to FIGURE 1, but showing a second modified version of the cistern;

FIGURE 10 is a fragmentary, vertical, axial section through a water outflow valve and an opening device therefor in a third modified version of the cistern;

FIGURE 11 is a fragmentary, vertical axial section through a modification of the opening device;

FIGURE 12 is a section taken on the line 12—12 of FIGURE 11;

FIGURE 13 illustrates a fragmentary, vertical axial section through a fourth modified version of the cistern, with a water outflow valve closed;

FIGURE 14 is a view similar to FIGURE 13, but with the water outflow valve open;

FIGURES 15 and 16 are views similar to FIGURE 13, but of fifth and sixth modified versions of the cistern;

FIGURE 17 is a view similar to FIGURE 1, but of a seventh modified version of the cistern.

Referring principally to FIGURES 1 to 5, the cistern includes a substantially fluid-tight container 1 which, in the example illustrated, is cylindrical and has a top wall 1a.

The base wall of the container 1 could be welded to the bottom of the side wall of the container, or could be separate therefrom and fixed therein as will now be described.

Secured to the inner periphery of the bottom of the side wall is an inverted annular channel-form member 2 the upper portion 2a of which is curved to receive and centre a compressible toroidal packing 3. The base wall 4 (see FIGURE 9) of the container includes a planar wall portion 4a (see FIGURE 6) which is laterally integral with a sloping annular wall portion 4b which at its outer periphery is integral with a curved, annular, channel-form, wall portion 4c which, with the portion 2a, bears in a fluid-tight manner against the packing 3. The pressure of the base wall 4 against the packing 3 is produced by an externally screw-threaded lower portion of the member 2. Instead of the ring there may be used a circlip disposed, after compression of the packing 3, in a circular groove in the member 2 extending under the portion 4c.

Centrally, the wall 4 is formed with a large-dimension aperture permitting the insertion and securing therein, by welding or the like, of a flushing pipe 6 (see FIGURE 4), whereas laterally a water inflow port 7, of a smaller through-flow area than is the water outflow port at the top of the pipe 6, debouches through the sloping wall portion 4b.

Internally, the container 1 is provided with a cover 8 the lower edge of the side wall 8a (see FIGURE 6) of which bears on the planar wall portion 4a.

The cover 8 is for example of cylindrical shape and is positioned on the wall 4 by means of peripheral projecting tongues 8c fitted or directly formed on the side wall 8a at pre-determined angular spacings. The tongues 8c may be resiliently engaged or otherwise secured in studs 4d fitted or directly formed on the portion 4b and corresponding in number and annular spacing to the tongues 8c.

In the example shown, this positioning is effected by means of three tongues 8c engaging in three corresponding studs 4d distributed at an angular spacing of 120°.

In the lower portion of the side wall 8a are cut apertures 8d which are circular in the example illustrated, and are uniformly spaced apart at the same level and provide communication between the interior of the container 1 outside the cover 8 and the interior of the cover 8.

Within the cover 8 commences the pipe 6 the widened initial portion of which provides the water outflow port and a frusto-conical valve seating 6a with which co-

operates a corresponding frusto-conical portion $9a$ of a valve closure member 9 centered in the cover 8 .

The valve closure member 9 is manufactured from a flexible or semi-rigid material, for example plastics material or rubber. Axially, it has extending through it a cylindrical hole receiving a conduit 10 of corresponding shape on which the member 9 is arranged to slide, preferably in a fluid-tight manner. Peripherally, the member 9 has a triangular cross-section a vertical face $9b$ of which is parallel to the side wall $8a$ leaving between the face $9b$ and the side wall a clearance e permitting passage of water between the chambers c^1 and c^2 formed within the cover 8 respectively below and above the cover 8 .

A compression spring 11 , mounted between the top wall $8b$ of the cover 8 and the top face $9c$ of the valve closure member 9 tends to urge the valve closure member against the seating $6a$ of the pipe 6 which the member 9 thus closes in a fluid-tight manner.

Various pilot means may be provided for bringing about an outflow of the water contained in the chamber c^2 , in such manner as to diminish the downward force exerted on the valve closure member 9 , this causing the opening of the valve closure member and resulting in the sudden freeing of the outflow port for the water contained in the cistern and, consequently, in the desired flushing effect. This pilot means may consist of a simple cock, or a lever with a valve closure member.

However, this pilot means preferably consists of a plunger-type valve requiring the application of a small thrust force to bring about the initiation of the flushing action. Accordingly, the plunger-type valve includes a plunger button 12 centered and freely slideable in a bearing face $13a$ of corresponding cross-section formed in one end of a sleeve 13 which is radially fixed in the pipe 6 . At its other end, the sleeve 13 is provided axially with a chamber $13b$ the peripheral wall of which has extending through it cylindrical perforations $13c$ which establish communication between the chamber $13b$ and the pipe 6 . The button 12 has fixed thereto co-axially a plunger rod $12a$ which is guided and slides in a fluid-tight manner in a packing 14 disposed at the inner end of the chamber $13b$ of the sleeve 13 . At its end opposite to the button 12 , the rod $12a$ carries two valve closure members in the form of frusto-conical lips $12b$ and $12c$ which increase in diameter in respective opposite axial directions. The valve lips $12b$ and $12c$ extend axially through a pilot valve closure member 15 the aperture $15a$ in which they are arranged to close alternately. The lip $12b$ is continually urged against the member 15 by a spring 16 mounted between the lip $12b$ and the outer end face of a chamber $17a$ of a plug 17 which is screwed into an internally screw-threaded sleeve 18 secured, by welding or the like, in the pipe 6 at a location diametrically opposite to the sleeve 13 . Co-axially relatively to the double valve and the member 15 there are formed two chambers c^3 and c^4 , which are provided by forming the lower end of the conduit 10 with two envelopes or cylindrical and co-axial walls $10a$ and $10b$ perpendicular to the conduit 10 .

The action of the spring 16 on the double valve tends to maintain the button 12 in a projecting position, to maintain the aperture $15a$ closed by the lip $12b$ of the double valve, and to maintain the member 15 abutted against the free circular end of the wall $10b$ which acts as the pilot valve seat, the result of this being to separate the chamber c^4 from the chamber c^3 and the conduit 10 . Furthermore, the member 15 , centered in the chamber c^3 , is provided at its outer periphery with a triangular lip $15b$ a horizontal face $15c$ of which is parallel to the cylindrical wall $10a$, leaving between it and the wall a clearance e^1 permitting communication between the conduit 10 and the chamber $17a$.

It will be clear that, in the version of FIGURES 1 to 5, the pilot means is mounted at the base of the cistern and directly in the pipe 6 . However, the pilot means may also be mounted at other points, for example in the case of a

cistern disposed at a relatively low level, at the upper part of the container as shown in FIGURES 6 to 8. In this version, the functioning of the flushing cistern is identical and the main features of the cover 8 mounted on the base wall 4 , the pipe 6 , the seating $6a$ thereof, the valve closure member 9 and the spring 11 are again present. However, the pilot valve has a cylindrical sleeve 19 of large dimensions for housing the parts of the valve. The sleeve 19 is secured in any known manner to the upper part of the container 1 and, preferably, to the centre of the top wall $1a$, as shown. Internally, the sleeve 19 has a smaller co-axial sleeve 20 forming the chamber c^4 and having communication perforations $20a$. A partition 21 having a sealing packing $21a$ separates the chamber c^4 and the chamber c^3 formed at the closed lower end of the sleeve 19 . The same arrangement as in the version of FIGURES 1 to 5 is provided in respect of the plunger button 12 , the plunger rod $12a$, the double valve, the spring 16 , and the pilot valve closure member 15 . However, the conduit 10 now extends upwards from the cover 8 to establish communication between the chamber c^2 and the chamber c^3 formed below the member 15 . An auxiliary conduit 22 leads from the chamber c^4 to the pipe 6 to permit the partial evacuation of the water contained in the sleeve 19 . A description will now be given of the operation of the two versions already described.

The water is admitted into the container 1 through the inflow port 7 . The water fills the container up to the point of equilibrium between the water pressure and the pressure of the air cushion compressed in the upper part of the container.

Through the apertures $8d$, the water penetrates into the cover 8 and provides opposing upward and downward pressures on the member 9 , the spring 11 maintaining the member 9 closed on its seating $6a$. The water also flows through the conduit 10 into the chamber c^3 . The water fills the chamber and, as it flows about the pilot valve closure member 15 , provides opposing axial pressures on the member 15 which is maintained in its closed position owing to the spring 16 acting on the double valve which, by means of its lip $12b$, closes the axial aperture $15a$. Thus, the filling of the cistern is effected (FIGURES 1 and 6).

On exertion of pressure on the button 12 , the lip $12b$ of the double valve is urged away from the aperture $15a$ against the action of the spring 16 (FIGURE 2). The water contained in the chamber $17a$ is able to flow, via the aperture $15a$ into the chamber c^4 and, via the apertures $13c$, or $20a$, into the pipe 6 .

As soon as this flow commences, the resultant force on the member 15 is reversed in direction, so that the pilot valve is opened, the pressure of the water in the conduit 10 urging away from the pilot valve seat the pilot valve closure member 15 the axial aperture $15a$ in which is now blocked by the lip $12c$ of the double valve (FIGURES 4 and 7), and the water flows under greater pressure into the pipe 6 . In this manner, the water contained in the chamber c^2 above the main valve closure member 9 is evacuated and an upward resultant force is established on the member 9 , so that the latter is raised against the action of the spring 11 (FIGURES 5 and 8). The flushing then takes place, with considerable force, via the pipe 6 .

At the end of the flushing operation, the resultant force on the member 9 is downward and urges the member 9 against its seating $6a$ whereupon the container 1 is re-filled.

A notable advantage of a control arrangement of this kind, operating by two successive effects involving differential pressures, will be readily apparent in that a slight pressure on the push button suffices to open the main valve which is however subjected to the considerable pressure of the water in the container.

A further advantage of the cistern resides in its silent operation, notably during filling, since the inflow of

water through the port 7 is effected directly, without constriction, and therefore without prolonged "whistling." There is always a small quantity of water in the bottom of the container, so that spurts entering the container from the port 7 are damped. This direct, unconstricted inflow of water is rendered possible because the main valve closure member is protected from turbulence and guided and retained by the cover 8. It will be noted that, as indicated in chain lines in FIGURE 1, the container 1 may contain a flexible diaphragm R which improves the silent operation of this flushing system. The diaphragm R is connected in a substantially fluid-tight manner at its periphery to the bottom of the side wall of the container round the whole circumference of the side wall.

Further versions of the pilot valve and its controls will now be described with reference to FIGURES 9 to 12.

Referring to FIGURE 9, a vertically slidable rod 23 is mounted in a fluid-tight manner in a tube 24 secured in any known manner to the centre of the top wall of the container 1 and of the cover 8. In its upper end, the tube 24 has a sealing and guiding packing 24a through which extends axially the rod 23 the upper end of which is visible above the container and carries a grasping ring 23a permitting the manual opening of the pilot valve. At its lower end, the tube 24 opens into the chamber c^2 through the flat top wall 8b of the cover 8 to which the tube is fixed in any known manner. Formed in the lower end of the tube 24 is a bulge 24b constituting a chamber c^5 in which is disposed packing 25, which may be of the stuffing box type for example having on each face a metal washer 25a. A compression spring 26, the upper end of which bears on the lower washer 25a, bears at its lower end on a washer 27a secured on the rod 23 above a pilot valve closure member 27 carried at the lower end of the rod 23. The member 27, which is for example of frusto-conical shape as shown, thus closes an axial hole 9d of circular cross-section extending through the member 9. As will be clearly understood, the action for initiating the flushing operation consists of a simple pull in the direction of the arrow F on the rod 23 to cause the member 27 to open and permit the preliminary flow through the hole 9d of the water contained in the upper chamber c^2 , whereby an upward resultant force on the member 9 then opens the latter.

FIGURE 10 shows a version in which the opening means for the pilot valve is directly mounted on the pipe 6. In this version, the member 9 centered in the cover 8 has extending axially through its hole 9d a slideable thrust rod 28 the upper end of which carries the pilot valve closure member 27. The member 27 is urged to close the hole 9d by a compression spring 29 mounted between the horizontal top wall 8b and a washer 30 secured to the rod 28 above the member 27. At its lower end, the rod 28 is guided by any suitable device, such as a ring 31 carried in the pipe 6 by radial bars so as not to hinder significantly the water flow. The lower extremity of the rod 28 bears continually, under the action of the spring 29, against an eccentric cam 32 fast with a turnable shaft 33 diametrically mounted in the pipe 6. The turning of the shaft 33 is manually performed by means of an arm 34 fixed to the end of the shaft 33 outside the pipe 6, the bearing faces of the shaft 33 in the pipe wall being rendered fluid-tight in any known manner. Turning of the arm 34 in the direction of the arrow F results in an angular displacement of the cam 32 which produces an upward thrust on the rod 28 to raise the member 27 and cause the flushing to occur.

Referring to FIGURES 11 and 12, in the modification the lower extremity of the thrust rod 28 bears in an eccentric groove 35a formed in the middle portion of a cam shaft 35 extending through the pipe 6, the cam thus being a cylindrical portion of the shaft having its axis parallel to the axis of rotation of the shaft. The shaft 35 is here again turnable by the external arm 34.

In the versions of FIGURES 13 to 17, the main valve closure member 9 is no longer mounted for sliding in the cover 8, but has its annular portion 9e projecting laterally beyond the seat 6a of a thickness which is such that the member 9 is sufficiently strong and yet may exhibit a degree of flexibility permitting, under the action of water pressure exerted upwardly or downwardly, deformation of the portion 9e in the manner to be described. The outer periphery 9f of the annular portion 9d is fixed by any appropriate means, and in a fluid-tight manner, on a ring 39, the arrangement being such as to tend to maintain the member 9 in its closed position on the seat 6a. Above the member 9 is a cover 37 the top wall 37b of which is formed with a water inlet opening 37c. The through-flow area of the opening 37c is changeable by for example fitting therein, during assembly of the cistern, a bush 38 from a number of bushes of differing diameter, the selected bush 38 having a diameter corresponding to the water supply pressure. Any other suitable means 37c may be utilised. The cover 37 bounds, above the member 9, the chamber c^2 receiving the necessary volume of water via the opening 37c, in such manner that a pressure giving fluid-tight closure is exerted by the member 9 on the seat 6a. It should be emphasised that the through-flow area of the opening 37c is substantially less than that of the outflow conduit 10, so that, during the initiation of the flushing operation, there is obtained in the chamber c^2 a lower pressure than that below the downwardly facing surface of the annular portion 9e.

In the version shown in FIGURES 13 and 14, the periphery 9f of the valve is provided with an upwardly and inwardly directed annular lip portion to form an annular seating 9g in which is engaged in a fluid-tight manner a laterally outwardly directed annular flange portion 37a of the cover 37. The latter is made for example from stamped sheet-metal.

The assembly comprising the member 9 and the cover 37 is centered by the periphery 9f in the circular ring 39 the inside 39a of which enables the water pressure to be exerted upwardly against the portion 9e. If necessary, depending on the mode of assembling the cistern, the cover 37, the member 9 and the ring 39 may be assembled by means of screws or the like.

The ring 39 may for example be carried by legs 40 appropriately distributed and secured to the ring which is at a suitable distance from the base wall 4. The legs 40 may bear freely on the wall 4. However, it is also possible to secure permanently the legs 40 to the wall 4, for example by welding. The ring 39 may also be carried in any suitable manner, with appropriate spacing, above the base wall 4.

The initiation stages of the flushing operation are basically identical with those previously described. When the push button 12 is pressed, there is produced a flow of the water contained in the chamber c^2 through the conduit 10. Owing to the difference between the inflow and outflow areas for the chamber an upward resultant force is produced on the member 9, as indicated by the arrow F^1 , deforming the member 9 which is thus raised from the seat 6a and opens the water outflow port through which the water in the cistern is evacuated. At the end of evacuation of the cistern, the water again enters the cistern through the port 7 and also enters the chamber c^2 through the opening 37c, in such manner as to fill the chamber c^2 under a pressure ensuring the closure of the pipe 6 as already described.

FIGURE 15 shows a version in which the cover has a side integral with the ring. This cover 41 includes a vertical cylindrical tube receiving at its bottom in a fluid-tight manner the circular periphery 9f of the member 9, the tube being closed at its upper end either by means of a separate fitted plate 41a, fixed in any suitable manner, or by a top wall integral with the tube.

FIGURES 16 and 17 show applications to the cistern

of FIGURE 13 of the pilot valves and controls therefor already described with reference to FIGURES 6 and 10.

Referring to FIGURE 16, the evacuation of the chamber c^2 is achieved by means of the arm 34 acting via the cam 32 on the push rod 28 carrying at its free end the pilot valve closure member 27 maintained by the spring 29 in a position closing the hole 9d formed in the member 9. It will be recalled that this device can instead include a slidable rod extending through the top wall of the container.

FIGURE 17 shows the pilot valve operable by means of a push button and mounted in the upper part of the cistern.

In the versions of FIGURES 13 to 17, owing to the resilient flexibility of the main valve closure member, it becomes possible to dispense with the compression spring provided in the previous versions and mounted in the cover. However, it is also possible to retain this spring, so as to obtain a more rapid return of the closure member after flushing.

In the versions of FIGURES 13 to 17, the base wall 4 is a stamped circular annulus the annular outer peripheral edge portion of which is turned down for resilient engagement in the bottom of the side wall of the container 1. The wall 4 may be secured to the side wall of the container by spot welding or by seam welding of the contiguous edges at s. Fluid-tightness of the peripheral joint is achieved by internally fitting the joint with a packing made of for example poured plastics material, or any other suitable packing. The pipe 6 is hard-soldered, at 4a, into the central aperture in the wall 4.

The flushing cistern has at its upper part, preferably in the top wall 1a, a non-return valve which, in the example illustrated in FIGURE 17, includes a hollow casing 36 secured by hard-soldering or other means in the top wall 1a of the container 1. Within the casing 36, a ball 36a is urged by a compression spring 36b against a corresponding seat formed in the upper portion of the casing 36. A port 36c, closable by the ball 36b, establishes communication between the interior of the container 1 and the ambient atmosphere. This non-return valve permits the automatic replacement of any air which may escape during the flushing action. In fact, at the end of the evacuation of water, a suction effect is set up in the container which causes a small inflow of air through the non-return valve, thus making it possible to maintain within the container a volume of air sufficient to produce the flushing effect.

I claim:

1. A hydro-pneumatic flushing cistern, comprising a container, portions of said container defining a water inflow port for feeding water to the interior of said container, a valve seat at the base of said container bounding a water outflow port of greater through-flow area than is said inflow port for leading flushing water from said container, a valve closure member in said interior movable between a closed position in which it contacts said seat and closes said outflow port and an open position which is above said closed position, biasing means urging said closure member away from said open position and towards said closed position, a cover covering said valve closure member, portions of said cover and said valve closure member defining therebetween a chamber, duct means communicating with said chamber for leading water thereto, said duct means comprising other portions of said closure member and said cover defining therebetween a lateral clearance, and portions of said cover below said lateral clearance bounding aperture means upstream of said clearance with respect to water flow to said chamber; and flow-producing means for producing a flow of water from said chamber such as to cause the upward force on said closure member to exceed the downward force on said closure member, whereby said closure member is opened.

2. A cistern according to claim 1, and further comprising a projecting portion of said closure member projecting laterally outwardly beyond said seat and providing a downwardly facing surface for the application of an opening force on said closure member by water in said container.

3. A cistern according to claim 1, wherein said flow-producing means comprises conduit means leading from said chamber and a pilot valve in said conduit means operable to permit flow of water from said chamber via said conduit means.

4. A cistern according to claim 3, wherein said pilot valve comprises a pilot valve housing, a pilot valve seat in said housing encircling a pilot valve port, a pilot valve closure member in said housing movable between a closed position in which it closes said pilot valve port and an open position, portions of said pilot valve closure member defining an aperture therein, an opening plunger extending through said aperture and movable longitudinally to a limited extent relatively to said pilot valve closure member for displacing said pilot valve closure member from its closed position to its open position, third and fourth valve closure members provided on said plunger and operable to close alternately said aperture, and pilot valve biasing means urging said pilot valve closure member away from its open position and towards its closed position, said pilot valve closure member having its side remote from said pilot valve seat exposed to the pressure in said chamber when in its closed position.

5. A cistern according to claim 3, and further comprising a flushing pipe leading downwardly from said water outflow port and having said pilot valve mounted therein, said conduit means opening into said pipe.

6. A cistern according to claim 3, and further comprising a top wall of said cistern having said pilot valve mounted therein, and a manually operable opening member of said pilot valve extending upwardly through said top wall, said conduit means extending from said chamber to said water outflow port via said pilot valve.

7. A cistern according to claim 3, wherein said conduit means comprises portions of said closure member defining a hole therethrough communicating said chamber with said water outflow port, and said pilot valve comprises a pilot valve closure member movable between a closed position in which it closes said hole and an open position above its closed position, pilot valve biasing means urging said pilot valve closure member away from its open position and towards its closed position, and pilot valve opening means operable to open said pilot valve closure member.

8. A cistern according to claim 7, and further comprising a top wall of said container, said pilot valve opening means comprising a longitudinally slid able member extending upwardly through said top wall and having said pilot valve closure member attached thereto.

9. A cistern according to claim 7, and further comprising a flushing pipe leading downwardly from said water outflow port, said pilot valve opening means comprising a longitudinally slid able member extending downwardly through said hole and of a cross-sectional area at said hole less than that of said hole and having said pilot valve closure member attached to the upper end thereof, a cam shaft turnably mounted in said flushing pipe, a cam provided on said cam shaft and co-operating with the lower end of said longitudinally slid able member for displacing the latter upwardly to open said pilot valve closure member, and an arm outside said pipe and said container and connected to said cam shaft for turning said cam shaft to turn said cam.

10. A cistern according to claim 9, wherein said cam comprises a substantially cylindrical surface portion of said shaft having its axis substantially parallel to the axis of turning of the shaft.

11. A cistern according to claim 1, wherein said biasing means comprises a flexible annular projecting portion of

said closure member projecting laterally outwardly beyond said seat round the whole circumference of said seat and providing a downwardly facing surface for the application of an opening force on said closure member by water in said container, said cistern further comprising a ring in said container stationary relative to said container and closely encircling the outer periphery of said projecting portion and having said outer periphery fixed thereto, and portions of said ring and the base wall of said container defining aperture means therebetween for permitting access of water to said downwardly facing surface, said cover extending to the region of said outer periphery and being connected to said outer periphery in a substantially fluid-tight manner round the whole of said outer periphery.

12. A cistern according to claim 11, wherein said duct means extends through said cover and is of a changeable through-flow area.

13. A cistern according to claim 12, and further comprising an opening through said cover leading to said chamber, said duct means comprising a bush removably fitted in said opening for interchanging with another bush removably fittable in said opening to change the through-flow area of said duct means.

14. A cistern according to claim 11, and further comprising supporting means attached to said ring and resting freely in said base wall and thus supporting said ring on said base wall.

15. A cistern according to claim 11, wherein said cover has a side wall integral with said ring round the entire circumference of said ring.

16. A cistern according to claim 15, wherein said cover has a top wall separate from said side wall but fitted thereto in a substantially fluid-tight manner.

17. A cistern according to claim 11, and further comprising an upwardly and inwardly directed annular lip portion of the valve closure member in the region of said outer periphery, and a laterally outwardly directed annular flange portion at the periphery of said cover engaged between said resilient annular projecting portion and said annular lip portion.

5 18. A cistern according to claim 1, wherein the base wall of said container is separate from the side wall thereof, said cistern further comprising an inverted annular channel-form member fixed in a fluid-tight manner round the inner periphery of the bottom of said side wall and projecting inwardly over said base wall, an annular packing extending in said channel-form member round the whole circumference thereof, and compressed between said channel-form member and said base wall, and clamping means maintaining said base wall pressed against said packing.

10 19. A cistern according to claim 1, wherein the base wall of said container is separate from the side wall thereof, said cistern further comprising a turned-down annular peripheral portion of said base wall adjacent to the bottom of said side wall and resiliently engaged in said bottom of said side wall, a weld securing said annular peripheral portion to said side wall, and an annular packing interposed in a substantially fluid-tight manner between said annular peripheral portion and said bottom of said side wall and extending round the whole circumference of said annular peripheral portion.

15 20. A cistern according to claim 1, wherein said container is substantially fluid-tight and has a top wall, said cistern further comprising a pre-loaded, non-return valve mounted in said top wall for automatically admitting air to compensate for loss of air from the interior of said container during the outflow of flushing water.
